CLAIM

The ornamental design for a column member for a pin puller tool assembly as shown and described.

DESCRIPTION

FIG. 1 is a rear perspective view of a first embodiment of a column member for a pin puller tool assembly according to our new and ornamental design.

FIG. 2 is a front perspective view thereof.

FIG. 3 is a side view thereof.

FIG. 4 is an opposite side view thereof.

FIG. 5 is a rear view thereof.

FIG. 6 is a front view thereof.

FIG. 7 is a top view thereof.

FIG. 8 is a bottom view thereof.

FIG. 9 is a rear perspective view of a second embodiment of a column member for a pin puller tool assembly according to our new and ornamental design.

FIG. 10 is a front perspective view thereof.

FIG. 11 is a side view thereof.

FIG. 12 is an opposite side view thereof.

FIG. 13 is a rear view thereof.

FIG. 14 is a front view thereof.

FIG. 15 is a top view thereof; and,

FIG. 16 is a bottom view thereof.
